UNITED STATES PATENT OFFICE.

EDWARD E. McCACKEN, OF GREENVILLE, PENNSYLVANIA.

TOWEL-DISPENSING CABINET.

1,104,207.

Specification of Letters Patent. Patented July 21, 1914.

Application filed May 8, 1913. Serial No. 766,404.

To all whom it may concern:

Be it known that I, EDWARD E. McCACKEN, a citizen of the United States, residing at Greenville, in the county of Mercer and State of Pennsylvania, have invented certain new and useful Improvements in Towel-Dispensing Cabinets, of which the following is a specification.

This invention relates to cabinets for containing and dispensing towels, and the object of my invention is to provide means for holding a supply of towels within a closed case in such manner that they are protected and may be dispensed one at a time, as required for use, and when used may be conveniently transferred to a receptacle for soiled towels without being detached from the cabinet.

In carrying out my invention, I provide a closed case containing a horizontally arranged rod on which a supply of towels is supported in rear of an opening in the case through which they may be withdrawn, one at a time. The rod is detachably connected at its rear end with the back of the case and at its front end is detachably connected with a vertically arranged rod which extends to a receptacle for soiled towels in the lower part of the case. The detachable connection between the front end of the horizontally arranged towel-supporting rod and the vertically arranged rod is normally locked and these rods can only be separated by the use of a key. The front end of the cabinet is provided with a door normally closed and opened only by the use of a key held by some authorized person. The door has an opening in its upper portion through which the towels may be withdrawn one at a time, and this opening is closed by a small door or cover which may be easily opened by any one. The main door is also provided, in its lower portion, with an opening through which the vertically arranged rod extends in order to guide the soiled towels to their receptacle in the lower part of the cabinet. I preferably also provide within the cabinet an extra supply of clean towels which may be supported on a horizontal rod similar to that first mentioned and which may replace the first-mentioned rod when the supply of towels carried thereby is exhausted. In order to hold the towels within convenient reach of the users, I provide a follower which engages the rear towel of the row and presses the row of towels automatically to-

ward the opening in the front door. This follower is connected by cords or wires with weights which press the row of towels forwardly and hold the front towel close to the front opening in the front door. I may also provide a case or cabinet for containing a larger supply of towels to be used when the supply in the dispensing cabinet is entirely exhausted. This case or cabinet is provided with a door which may be locked and only opened by authorized persons and the towels may be supported on rods similar to the horizontal rods before mentioned and adapted to connect with the vertically arranged rod which guides soiled towels to their receptacle in the case.

In the accompanying drawings:—Figure 1 is a perspective view of a towel-dispensing cabinet embodying my improvements. Fig. 2 shows a vertical central section thereof. Figs. 3 to 6 are on an enlarged scale. Fig. 3 is a detail view, showing particularly the construction of the horizontally arranged towel-supporting rod and indicates how it is supported at its rear end and how its front end is detachably connected with the vertically arranged rod for guiding soiled towels to their receptacle. Fig. 4 is a detail view in section of the upper end of the vertically arranged guide-rod. Fig. 5 is a detail view of the front end of the horizontally arranged towel-supporting rod. Fig. 6 shows, on an enlarged scale, a section on the line 6—6 of Fig. 3. Fig. 7 is a detail view, on an enlarged scale, showing particularly the horizontally arranged towel-supporting rod and the follower carried thereby which moves the row of towels toward the front of the cabinet. Fig. 8 is a perspective view of a case or cabinet which may be employed for holding an extra supply of clean towels. Fig. 9 is a detail view, showing how a row of clean towels may be supported within the cabinet on a rod adapted to enter the towel-dispensing cabinet and to connect with the vertically arranged guide-rod thereof. Fig. 10 is a detail view, in perspective, of a clip or catch which may be employed to hold the towels on the rod while in the cabinet, shown in Fig. 8.

The towels A are contained within a case or cabinet B, which is tightly closed so as to protect the towels from dust and other contamination. This case or cabinet may be constructed of any suitable material, and it is provided with a front door B' which is

kept locked, *b* indicating the key-hole. The door is provided with an opening *B*² to receive soiled towels which are deposited in the lower portion *B*³ of the case. The towels 5 are preferably folded in the manner indicated and they are strung on a horizontally arranged rod *C*. For this purpose the towels may be provided at one end with holes or gromets, and this rod *C* has a bent 10 rear end *c*² adapted to fit in a socket *D* attached to the back wall of the case *B* in such manner that it may be readily detached therefrom. The rod *C* is detachably connected at its front end with a vertically arranged rod *E* having a short horizontal portion *e* at its upper end with which the rod *C* engages. The rod *E* has an upper portion which is arranged in front of the door *B*' and at its lower end this portion 15 connects with an inclined portion *e*' which extends through the opening *B*² and enters the cabinet. The lower rear end of the rod may be connected with a socket *F* in the bottom of the cabinet. The detachable connection between the rod *E* and the rod *C* is 20 indicated in detail in Figs. 4, 5 and 6. As shown the rod *C* has a forwardly projecting arm *c* formed with a notch *c*'. The arm *c* enters a socket *e*² in the rod *E* and the 25 notch *c*' engages a latch *G*, normally pressed inward by a spring *g*. The arrangement is such that when the arm *c* is forced into the socket *e*² the latch engages the arm and holds the rods *C* and *E* in a locked condition. The 30 two rods may, however, be disengaged by means of a key *K*. The rod *E* extends through an opening *H* in the upper portion of the cabinet which is closed by a door *I* which door may be operated by a handle *i*. 35 This door may be glazed, as indicated, and is formed with an opening *i* to permit the rod *E* to pass through it.

As shown a series of towels is strung on the rod *C* and in order to hold the towels 40 close to the opening in the front door of the cabinet I provide a follower *L* which is drawn forward by weights *M*, connected with the follower by cords or wires *m*, passing over pulleys *m'*. Preferably the follower 45 is constructed and arranged in the manner shown in Fig. 7, where it is shown as comprising a cross-piece *l*, resting on and guided by the rod *C*, and provided with downwardly extending arms *l'* which engage the rearmost towel in the series. By 50 this arrangement the towels will be pressed close together and moved toward the front opening as fast as towels are withdrawn from the front of the series. To withdraw 55 a towel it is only necessary for the user to raise the door *I*, catch hold of a towel, draw it forward through the opening and use it and then let it drop when it will be guided by the guide-rod *E* into the receptacle for soiled towels in the lower portion 60 65

of the cabinet. I preferably provide the cabinet with an additional rod *C*, carrying another supply of towels. This rod may be supported in a socket *D* in the manner indicated and when required the rod may be 70 lifted from its socket and placed in the socket *D* above it and connected with the rod *E* in the manner before described. It is also possible to have additional rods with extra supplies of towels which may be removed by the attendant or some authorized person when the door *B*' is opened and connected with the rod *E* as before explained. I preferably, however, have close at hand a case or cabinet *N* provided with a door *N*' 75 controlled by lock and key, and within this cabinet I provide sockets *n* to receive rods *C* similar to those before described. 80

In order to hold the towels in place on each rod a clip or catch *O* may be employed. 85 This catch comprises an arm *o*, perforated at *o*' to fit on the arm *c*, and also a part *o*'', the end of which is adapted to engage the notch *c*'. The clip may be readily removed when it is desired to connect the rod *C* 90 with the vertical rod *E*. The cabinet may be arranged to contain a large number of rods with towels thereon.

A towel-dispensing cabinet of the construction described may be made cheaply 95 and will be serviceable in many places. The towels are kept clean. No one of them can be entirely separated from the cabinet by an unauthorized person. A fresh towel is always within convenient reach of the user, 100 and after being used the soiled towel if merely dropped will be automatically guided into a receptacle where it will be concealed.

I claim as my invention:—

1. A towel-dispensing cabinet, comprising 105 a casing in the upper portion of which clean towels are stored and in the lower portion of which soiled towels are received, a door to the cabinet having an opening in its upper portion for the withdrawal of 110 clean towels and an opening in its lower portion for permitting the passage of soiled towels to the lower portion of the cabinet, a horizontally arranged towel-supporting rod in the upper portion of the cabinet detachably connected with the cabinet at its rear end, and a vertically arranged rod locked to but detachably connected with said horizontally arranged rod inside the door of the cabinet and which extends through the 115 upper opening in the cabinet door and projects downwardly therefrom to and through the opening for soiled towels and which guides soiled towels to the interior of the cabinet. 120

2. A towel dispensing cabinet, comprising 125 a closed casing having a front door provided with an opening in its upper portion for the withdrawal of clean towels and an opening in its lower portion to receive soiled 130

towels, a door for the opening in the upper portion of the cabinet, a towel-supporting rod in the upper portion of the cabinet which is detachably connected with the cabinet, a vertically arranged rod extending through the opening in the upper portion of the cabinet and extending downwardly and through the opening in the lower por-

tion thereof and detachable locked connections within the cabinet between said rods. 13

In testimony whereof, I have hereunto subscribed my name.

EDWARD E. McCACKEN.
